(No Model.)

A. AYRES.

RAILWAY SWITCH.

No. 311,801.

Patented Feb. 3, 1885.

UNITED STATES PATENT OFFICE

ABRAHAM AYRES, OF NEW YORK, N. Y.

RAILWAY-SWITCH.

SPECIFICATION forming part of Letters Patent No. 311,801, dated February 3, 1885.

Application filed April 15, 1884. (No model.)

To all whom it may concern:

Be it known that I, ABRAHAM AYRES, of the city, county, and State of New York, have invented certain new and useful Improvements in Railroad-Switches, of which the following is a full, clear, and exact description.

Reference is to be had to the accompanying drawings, forming part of this specification, in which similar letters of reference indicate corresponding parts in all the figures.

Figure 1 is a plan view of a railroad-switch to which my improvement has been applied, part being broken away. Fig. 2 is a sectional end elevation of the same, taken through the broken line *x x x*, Fig. 1. Fig. 3 is a sectional side elevation of the same, taken through the broken line *y y*, Fig. 2. Fig. 4 is a plan view of the jointed end of a part of the connecting-rod, the fastening-bolts being shown in section.

20 The object of this invention is to facilitate the adjustment of the operating parts of a railroad-switch and promote convenience in the use of such switches.

The invention consists in the construction and arrangement of parts, as will be herein-after fully described and claimed.

A represents the box or case of the switch. The side parts of the top of the case A are rabbeted to receive the switch-plates B, of 30 which C are the rails of the main track, D the rails of the branch track, E the stationary tongue, and F the movable tongue.

G are the side sections of the oscillating plate, the ends of which are formed upon the 35 end parts of two cross-bars, H.

Upon the outer sides of the centers of the cross-bars H are formed recessed or socket lugs I, which rest and oscillate upon pivot-lugs J, attached to the inner sides of the upper 40 parts of the case A. The movement of the oscillating plate G H is limited by lugs K, formed upon or attached to the lower parts of the inner edges of the switch-plates B. The space between the side sections, G, is filled

45 by a plate, L, the ends of which rest in rabbets M in the top edges of the ends of the case A, so that the central section, L, will be stationary, and will be held securely in place. The central section, L, is provided with ring-handles N, placed in recesses in its upper sur-

face, so that the said handles, when not in use, and when turned down into the said recesses, will be flush with or a little below the surface of the said plate L. With this construction the central plate, L, can be readily removed to give convenient access to the interior of the switch.

To the movable tongue F is attached a pin, O, which passes down through a short cross-slot, P, in the plate B, between the rails C D. The lower end of the pin O passes through an eye in the end of the connecting-rod Q, which is secured in place upon the said pin by a pin or nut. The other end of the connecting-rod Q is pivoted to the lower arm of the elbow-lever R, which is pivoted at its angle to the upper end of the slotted standard S, formed upon or attached to the cross-bar T, secured to the lower part of the case A. The upper arm of the elbow-lever R is forked, and is pivoted to a lug, U, attached to or formed upon the side section, G, of the oscillating plate, so that the tongue F will be moved by the oscillation of the said plate. The connecting-rod Q is made in two parts or sections, the 75 adjacent ends of which overlap and are secured to each other by three (more or less) bolts, V. The overlapped adjacent ends of the sections of the rod Q have short longitudinal slots W formed in them to receive the 80 bolts V, so that by loosening the nuts of the bolts V the said rod Q can be slightly lengthened or shortened, so that the oscillation of the plate G H can be made to give to the tongue F exactly the amount of movement required in adjusting the said tongue. The oscillating plate is operated by the weight of the animal drawing the car. If the animal is driven on the right or left hand plate G, the pivoted tongue will be moved toward or from 85 the main rail, thus permitting the car to run on the main rails or be automatically switched to the branch rails D.

Having thus described my invention, I claim as new and desire to secure by Letters Patent— 95

1. The combination, in a railroad - switch, with the oscillating plate G H, elbow-lever R, and pivoted tongue F, of the sectional rod Q, connected at its opposite ends to the elbow-lever and tongue, and provided with slots W 100

in its adjacent overlapped ends, and the fastening-bolts V, for adjusting the length of the rod to give exactly the necessary amount of movement to the switch-tongue, substantially as set forth.

2. A railroad-switch of the character described, consisting, essentially, of the casing A, main and branch tracks C D, fixed and movable tongues E F, frame G H, pivoted at J, stationary central section, L, standard S,

bell-crank lever R, pivoted thereto and pivotally connected to one side of the oscillating frame, pin O, extending from the pivoted tongue through the casing, and the rod Q, connecting said pin and the lower end of the lever R, substantially as set forth.
